NURSING ATTACHMENT FOR BOTTLES.

Application filed June 10, 1926. Serial No. 115,100.

The present invention relates to nursing attachments for bottles and has for its prime object to provide an attachment designed to adapt bottles, such as vacuum bottles, for use as a nursing bottle.

A further object of the invention is the provision of an attachment formed so as to be conveniently mounted in association with a vacuum bottle or the like and adapted to receive thereon the usual form of nursing nipple.

A still further object of the invention is the provision of a nursing attachment which may be detachably mounted on a vacuum bottle in place of the usual cap carried thereon.

Still another object of the invention is the provision of an attachment of the above character by means of which a vacuum bottle of ordinary construction may be converted for use as a nursing bottle.

Another object of the invention is the provision of an attachment of the above type which is simple and durable of construction and efficient for the purpose intended.

Other objects and advantages of the invention will become apparent as the description progresses.

In the accompanying drawing forming a part of this specification and in which like reference characters are employed to designate corresponding parts throughout the same,

Figure 1 is a fragmentary side elevational view of a conventional vacuum bottle illustrating our improved attachment as applied thereon,

Figure 2 is a top plan view of the attachment shown in Figure 1,

Figure 3 is a side elevational view of a modified form of attachment disclosing the application of a nipple thereon, and

Figure 4 is a top plan view of the attachment shown in Figure 3.

Referring to the drawing wherein for the purpose of illustration is shown a preferred and a modified form of our invention, the numeral 10 generally designates a vacuum bottle of conventional construction, provided at its upper end with a screw threaded neck 11. This type of bottle is usually enclosed by a detachable cap screw-threaded at its lower end for engagement with the threads formed

on the neck 11 and applicable for use as a drinking cup.

The primary feature of our present invention is the formation of an attachment in the form of a cap ring 12, the preferred form of which is illustrated in Figures 1 and 2. This ring is preferably constructed of glass or aluminum, or other suitable material and is generally cylindrical in configuration. The lower portion of the ring 12 is formed to provide screw threads 13 adapted to threadedly engage the threaded neck 11 of the vacuum bottle. The upper portion of the attachment is of straight cylindrical form and the upper and lower edges are provided with peripheral beads 14. These beads tend to re-enforce the structure of the cap ring and, the upper bead will prevent accidental displacement of the nursing nipple 15. It is of course well known, that the lower peripheral edge of the common form of nursing nipple is provided with an interior bead 16 which will engage the lower edge of the peripheral bead 14 and retain the nipple in proper position thereon.

It is obvious, from the foregoing description, that the bottle attachment described in the foregoing is adapted for use in connection with nursing nipples having a comparatively large body and therefore capable of application upon this type of cap ring. In order to accommodate nipples having a body structure of smaller diameter, we contemplate the production of an attachment designed particularly for this purpose, this type of attachment forming the modified form of our invention.

Referring now with particularity to the modified form of our invention as illustrated in Figures 3 and 4 of the drawing, the numeral 17 generally designates the lower portion of a cap ring which is of comparatively large diameter and formed with screw threads 18 for connection with the threaded neck 11 of a vacuum bottle. The intermediate portion of this cap ring is of tapered formation as at 19 terminating in an upper reduced neck portion 20. Thus, it is clearly apparent that the present type of attachment is in the form of a reducer fitting. An exterior peripheral bead 21 is formed about the upper edge of the neck 20 and a similar bead 22 of reduced cross sec-

tional area is formed at the lower edge. These annular beads will re-enforce the cap ring structure so as to increase the durability thereof and the upper bead will additionally serve to maintain a nursing nipple 23 in proper position on the cap ring. This form of nursing attachment will facilitate the use and attachment of the common small type of nursing nipple upon the vacuum 10 bottle of ordinary construction.

The forms of nursing attachments forming the subject matter of the foregoing description present means whereby a conventional type of vacuum bottle may be quickly 15 adapted for use as a nursing bottle so as to permit suitable attachment thereon of a nursing nipple. This invention will obviate the necessity of transferring the milk from the vacuum bottle to a special nursing bottle 20 and avoid all necessary exposure of the milk. Furthermore, it will be noted that the vacuum bottle need not be permanently employed for this particular application and may retain its original function of a container for ordinary liquids. 25

It is to be understood that the form of our invention herewith shown and described is to be taken as the preferred example of the same, and that various changes as to the shape and size thereof may be resorted to 30 without departing from the spirit of the invention or the scope of the subjoined claim.

Having thus described our invention, we claim:—

The combination with a vacuum bottle 35 having a screw threaded neck, of a nursing nipple attaching device, comprising a relatively short cylindrical body open at each end, screw threads formed at and in one end of the body engageable with the threaded 40 neck of the bottle, and a peripheral bead formed about the other end of the body upon the outer face of the wall thereof, adapted to have the lip of a nipple engaged thereover. 45

In testimony whereof we affix our signatures.

LEONARD A. PFISTER.
EDWARD V. HEUGHAN.
JOHN P. MARSE.
